Primary Examiner — Natasha Vujcic*(74) Attorney, Agent, or Firm* — Andrew C. Cheng(57) **CLAIM**

We claim the ornamental design for a chiller, as shown and described.

DESCRIPTION

FIG. 1 is a front, left-side, and top perspective view of a chiller showing our new design;

FIG. 2 is a rear, right-side, and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of an encircled portion 9 of FIG. 1; and,

FIG. 10 is an enlarged view of an encircled portion 10 of FIG. 1.

The broken lines depict portions of the chiller in which the design is embodied that form no part of the claimed design.
